UNITED STATES PATENT OFFICE.

EMIL HANTSCHÉ, JR., OF NEW YORK, N. Y.

WINDOW-BLIND.

SPECIFICATION forming part of Letters Patent No. 425,542, dated April 15, 1890.

Application filed January 22, 1890. Serial No. 337,719. (No model.)

To all whom it may concern:

Be it known that I, EMIL HANTSCHÉ, Jr., of New York city, New York, have invented an Improved Window-Blind, of which the following is a specification.

This invention relates to that class of window-blinds in which the rod that operates the slats is concealed within a cavity formed within one of the stiles.

It consists in the various features of improvement more fully pointed out in the claim.

In the accompanying drawings, Figure 1 is a sectional elevation of a window-blind provided with my improvement. Fig. 2 is a longitudinal section on line $x-x$, Fig. 1; Fig. 3, a transverse section on line $y-y$, Fig. 2; Fig. 4, a perspective view of the cap d , and Fig. 5 a bottom view thereof.

The letter a represents the blind-frame, one of the stiles a' of which is slotted longitudinally to receive the blind-operating mechanism.

b are the slats, pivoted by pivots c at one end in the usual manner, while at the other end they carry flattened tenons c' , that are embraced by caps d , made of malleable metal. The caps d are of the form shown in Fig. 4—that is to say, they are provided with two jaws d' , a toothed crown d^2 , and outwardly-projecting pivot d^3 . The two jaws d' are slipped over the flattened tenon c' , and are then pressed together to tightly grasp the tenon between them.

For the passage and reception of the caps d the slotted stile a' is provided with the enlarged openings a^2 , which, however, do not form the bearings in which the slats turn. These bearings are formed by a plate e , placed

within stile a' , and which is perforated in line with each pivot d^3 . The several perforations receive the ends of pivots d^3 , Fig. 1, so as to permit the pivots to turn freely therein.

For the proper operation of the slats I employ a rack f , placed within the slotted stile a' and engaging the toothed crowns d^2 of the caps d . The rack carries a knob f' , by which it may be moved up or down to open or close the slats.

It will be seen that by the use of the bearing-plate e , placed within the hollow body of stile a' , the openings a^2 in such stile are relieved from the function of serving as bearings for the slats. As these openings are necessarily large, and therefore apt to wear out in use, it is of importance to take any strain or wearing contact away from them.

By the use of the two jaws d' , that grasp the tenon c' from opposite sides, I obtain that advantage over an ordinary socket that I may tightly press the jaws against the tenon to firmly unite the parts and prevent dead motion, and that the body of the tenon need not be unnecessarily cut down and weakened.

What I claim is—

The combination of a blind-frame having slotted stile a' , that is provided with openings a^2 , with slats b , toothed caps d , received by openings a^2 and having rearwardly-extending pivots d^3 , bearing-plate e within stile a' and receiving such pivots, and a rack f for engaging the toothed caps, substantially as specified.

EMIL HANTSCHÉ, JR.
